CIRCUIT CONTROL DEVICE

Bascum O. Austin and Richard H. Herman, Lima, Ohio, assignors to Westinghouse Electric Corporation, East Pittsburgh, Pa., a corporation of Pennsylvania

Application November 16, 1950, Serial No. 196,066

4 Claims. (Cl. 317—37)

1

Our invention relates, generally, to circuit control devices and, more particularly, to devices for controlling the operation of electromagnetically operated circuit breakers or contactors.

An object of our invention, generally stated, is to provide a device for controlling the operation of an electromagnetically operated contactor which shall be simple and efficient in operation and which may be economically manufactured and installed.

A more specific object of our invention is to provide a thermally responsive device for controlling the opening of an electromagnetically actuated contactor.

Another object of our invention is to provide a device for automatically opening a contactor upon an overload condition and which may be remotely controlled by a manually operable switch connected to the device through a single conductor.

A further object of our invention is to provide for remotely controlling the reclosing of an electromagnetically actuated contactor after being opened by an overload condition.

Other objects of our invention will be explained fully hereinafter or will be apparent to those skilled in the art.

In accordance with our invention, a main contactor, a thermally responsive tripping means, a control switch and trip resistors are mounted on a common base. The operation of the contactor may be controlled by means of a manually operable switch located remotely from the unit assembly. This switch has an overload trip which is actuated as the result of the operation of the control switch by the thermal element to connect the trip resistors in the circuit for the overload trip, thereby preventing the automatic reclosing of the contactor after being opened by the thermal element.

For a better understanding of the nature and objects of our invention, reference may be had to the following detailed description, taken in conjunction with the accompanying drawings, in which:

Figure 1 is a view, in top plan, of a contactor and control unit assembly embodying the principal features of the invention, part of the cover for the unit being broken away;

Fig. 2 is a view, partly in side elevation and partly in section, of the unit shown in Fig. 1;

Fig. 3 is a view, in bottom plan, of the unit shown in Fig. 1;

Fig. 4 is a view, in section, taken along the line IV—IV of Fig. 3, and

2

Fig. 5 is a diagrammatic view showing the control circuit connections for the contactor and its associated apparatus.

Referring to the drawings, the structure shown therein comprises an insulating base 10 upon which is mounted an electromagnetic contactor 11, a control switch 12 and a pair of resistors 13. A recess 14 is provided in the bottom side of the base 10 in which is mounted a bimetal plate 15. As shown most clearly in Fig. 2, a cover 18 may be attached to the base 10 by means of screws 19 which are threaded into brackets 21 on the cover 18. The cover 18 protects the contactor 11, the control switch 12 and the resistors 13. As shown in Fig. 4, a cover plate 22 may be attached to the bottom of the base 10 to protect the bimetal plate 15.

As shown most clearly in Figs. 1 and 2, the contactor 11 comprises a U-shaped frame 23, a coil 24 and a movable core 25 which is disposed inside of the coil 24. Contact bars 26 and 27 are attached to an insulating member 28 by bolts 29. The member 28 is attached to one end of the frame 23 by means of a metal plate 31 and screws 32.

A bridging contact member 35 is disposed to engage contact members 36 and 37 mounted on the contact bars 26 and 27, respectively. An arcing contact member 38 is disposed to bridge contact members 39 and 41 also mounted on the contact bars 26 and 27, respectively.

As shown most clearly in Fig. 1, the bridging contact member 35 and the arcing contact member 38 are carried by the movable core 25. A compression spring 42 is disposed between the insulating member 28 and the bridging contact member 35. Another compression spring 43 is disposed between the arcing contact member 38 and a cup washer 44 attached to the end of the core 25. A guide bar 45 is disposed to guide the movement of the bridging member 35 and the arcing contact member 38 as the core 25 is drawn into the coil 24 when it is energized, thereby closing the bridging contact members and the arcing contact members.

The control switch 12 may be of a type well known in the art and is a single pole double-throw switch having a snap action with automatic return. The control switch may be attached to the base 10 by means of a U-shaped bracket 46 and screws 47.

As shown most clearly in Fig. 4, the control switch has an actuating plunger 48 which actuates a contact arm 49. The contact arm 49 is so biased by a spring 50 that it returns to its normal po-

sition, as shown in the drawings, when pressure is removed from the plunger 48. Terminal members 51, 52 and 53 are provided on the control switch 12 for making the necessary electrical connections.

The resistors 13 are also of a standard construction. Terminal members 54 are provided on the resistors for making electrical connections to the resistors. Main contact studs 55 and 56 are provided for making the main circuit connections to the control unit. Secondary contact studs 58 are provided for making the control connections to the unit.

As explained hereinbefore, our invention provides for causing operation of the contactor 11 in response to overloads in the circuit controlled by the contactor. The bimetal plate 15 is utilized in controlling the operation of the contactor 11.

As shown most clearly in Fig. 3, the bimetal plate 15 is of a triangular shape. The base of the plate 15 is rigidly attached to the insulating base 10 by screws 61 and the bimetal is electrically connected in series with the main circuit which is controlled by the contactor 11. The remainder of the bimetal plate 15 is mechanically free and will deflect a certain amount corresponding to the temperature rise in the bimetal, which rise in temperature takes place when there is an increase in the amount of current flowing in the power circuit and through the bimetal plate. The free end of the bimetal is provided with an adjustable screw 62 which is disposed to engage the lower end of the plunger 48 for the control switch 12. It will be understood that the bimetal may be heated by a resistor connected in the main circuit if it is so desired. However, the structure may be simplified by connecting the bimetal directly in the main circuit as shown in the drawings.

As shown in Fig. 5, a switch 65, which is manually operable to open and close its contacts, is located remotely from the control unit assembly. The switch 65 is preferably a thermal circuit breaker having a thermally operated tripping mechanism comprising a bimetal 66 which bridges contact members 67 and 68 when a handle 69 is actuated to the closed position. The handle 69 is biased to the open position, as shown in the drawings, by a spring 71. The bimetal 66 is biased to the position shown in the drawings by a spring 72. The circuit breaker is so constructed that when a predetermined current flows through the bimetal 66 it is actuated to interrupt the circuit through the contact members 67 and 68 and to permit the handle 69 to be returned to the open position by the spring 71.

Referring to Fig. 5, it will be seen that when the circuit breaker 65 is closed to bridge the contact members 67 and 68 a circuit extends from positive through the contact members 67 and 68, conductor 75, contact members 49 and 76 of the control switch 12, the conductor 77, the actuating coil 24 of the contactor 11 and conductor 78 to ground. The energization of the coil 24 closes the contact members of the contactor 11, thereby connecting the bimetal plate 15 in series-circuit relation with the load circuit which is connected to the terminals 55 and 56.

Upon any fault or overload condition sufficient to actuate the bimetal plate 15 the contact member 49 of the control switch 12 is disengaged from the contact member 76 and engages a contact member 79. This operation of the control switch 12 deenergizes the coil 24 of the contactor 11, thereby opening the circuit through the contact

members of the contactor. The operation of the switch 12 also establishes a circuit through the resistors 13. The establishment of the circuit through the resistors 13 causes sufficient current to flow through the bimetal 66 of the circuit breaker 65 to operate the circuit breaker to interrupt the control circuit.

When the bimetal plate 15 cools down following the opening of the main power circuit by the operation of the contactor 11, the contact member 49 of the control switch 12 is automatically returned to its normal position. However, the contactor 11 is not reclosed since the circuit breaker 65 has been tripped and it must be reclosed manually in order to reclose the contactor 11. In this manner the contactor 11 is automatically opened by an overload condition but it must be manually reclosed following the clearing of the overload or fault condition. It will be noted that only one wire is required between the circuit breaker 65 and the control unit which is located remotely from the circuit breaker.

From the foregoing description it is apparent that we have provided for controlling the operation of an electromagnetically actuated contactor or circuit breaker in a simple and efficient manner. The device herein disclosed provides for automatically opening the contactor upon an overload or fault condition and requires that the contactor be manually reclosed upon the clearance of the fault condition. The device is simple in construction and light in weight, thereby making it particularly suitable for utilization on aircraft. Furthermore, the amount of wiring connections is reduced to a minimum.

Since numerous changes may be made in the above described construction and different embodiments of the invention may be made without departing from the spirit and scope thereof, it is intended that all matter contained in the foregoing description or shown in the accompanying drawings shall be interpreted as illustrative and not in a limiting sense.

We claim as our invention:

- 45 1. A control device comprising a contactor for controlling a load circuit, said contactor having an operating coil, a control switch having a normally closed contact connected in series with said coil and a second contact connected to an alternative circuit, a remote circuit breaker connected to the control switch for completing an energizing circuit for the coil, said circuit breaker including means for tripping the breaker in response to excess current, and means for actuating the control switch in response to excessive current in the load circuit to cause the control switch to open said normally closed contact to deenergize the coil and to close said second contact to complete the alternative circuit to the circuit breaker to effect tripping of the breaker.
- 50 2. A control device comprising a contactor for controlling a load circuit, said contactor having an operating coil, a control switch having a normally closed contact connected in series with said coil and a second contact connected to an alternative circuit, a remote circuit breaker connected to the control switch for completing an energizing circuit for the coil, said circuit breaker including means for tripping the breaker in response to excess current, and thermally-responsive means heated by the current in the load circuit for actuating the control switch in response to excess current to cause the control switch to open said normally closed contact to deenergize the coil and to close said second contact to com-

plete the alternative circuit to the circuit breaker to effect tripping of the breaker.

3. A control device comprising a contactor for controlling a load circuit, said contactor having an operating coil, a control switch having a normally closed contact connected to said coil and a second contact connected to a resistor, means for connecting the coil and resistor to a source of electrical energy, a remote circuit breaker connected to said control switch for completing a circuit to said source for energizing the coil, said circuit breaker including means for tripping the breaker in response to excess current, and means responsive to excessive current in the load circuit for actuating the control switch to open said normally closed contact to deenergize the coil and to close said second contact to complete an alternative circuit including the resistor to effect tripping of the circuit breaker.

4. A control device comprising a contactor for controlling a load circuit, said contactor having an operating coil, a control switch having a normally closed contact connected to said coil and a second contact connected to a resistor, means

for connecting the coil and resistor to a source of electrical energy, a remote circuit breaker connected to said control switch for completing a circuit to said source for energizing the coil, said circuit breaker including means for tripping the breaker in response to excess current, and thermally-responsive means heated by the current in the load circuit for actuating the control switch in response to excessive current to open said normally closed contact to deenergize the coil and to close said second contact to complete an alternative circuit including the resistor to effect tripping of the circuit breaker.
